MACHINE FOR SPINNING PAPER.

1,206,926.

Specification of Letters Patent.

Patented Dec. 5, 1916.

Application filed March 15, 1915. Serial No. 14,604.

To all whom it may concern:

Be it known that we, EDWARD SCHMIDT, a subject of the Emperor of Austria-Hungary, WALTER STEFFENS, a subject of the Emperor of Germany, and FRANK F. REINKE, a citizen of the United States, all residing at Cleveland, in the county of Cuyahoga and State of Ohio, have invented certain new and useful Improvements in Machines for Spinning Paper, of which the following is a specification.

This invention pertains to an improvement in a machine for spinning paper, and the improvement consists more particularly in the novel and useful mechanism for maintaining a flat strip of paper under tension during spinning operations, all substantially as herein shown and described and more particularly pointed out in the claims. In machines of this character, the paper strip is moistened to facilitate spinning operations, and the object of this improvement is to produce uniform saturation and sufficient tension continuously without tearing or severing the paper strip under the pulling and twisting strains of spinning operations.

In the accompanying drawings, Figure 1 is an end elevation of a sectional portion of a spinning machine containing the present invention; Fig. 2 is a front elevation of the machine; Fig. 3 is a transverse section, enlarged, of the front upper portion of the machine, and Fig. 4 is an enlarged end elevation of the same portion of the machine looking in from the right, showing the operating gears for the several tension and moistening rolls or rollers for the paper strip. Fig. 5 is a plan view of the mechanism shown in Fig. 3, and Figs. 6 and 7 are end and front views, respectively, of the same parts.

The machine as thus shown comprises a main supporting frame F, a series of spinning spindles S vertically disposed at the front of said frame and driven by power connections of any approved kind, belts g seen in Fig. 1 being used in this instance to convey the power. Now describing the mechanism coöperating with one of the spinning spindles, the paper strip 2 is brought to the machine in a roll R mounted on a suitable spool which is removably supported on a short stud shaft 3 at one side of a standard f fixed upon the main frame F, and feeding of the paper strip is directly downward

from the front side of the roll R to a gravity device or weight w adapted to rest upon the flat paper strip and supported by a table or platform 4 on the top of the machine and beneath which weight the dry paper strand or strip is drawn under the desired tension. Thence the paper passes upward and forward over a shaft 6 between spaced collars 6' and thence forward over a relatively wide idler roll 7 and downward to the tension and dampening rolls 8 and 9, respectively. The strip 2 passes down behind roll 8 and forward and between both rolls and thence downward on a substantially straight line to the spinning spindles S which rotate rapidly to twist or spin the strip and also to wind it upon the spinning spool. Manifestly, the strip is under a certain degree of tension from the spinning spool upward but to avoid breakage of the strip which is wet, the feeding of the strip is materially assisted by rolls 8 and 9 before the paper is weakened to any great degree by absorbing the water which is carried to the strip by roll 9. Moisture in the desired quantity is carried forward from the reservoir 10 by the successive rollers 11 and 12 to the roller 9, the roller 11 dipping into said reservoir and the roller 12 being in contact therewith and with roller 9. The said rollers 9 and 12 are supported on suitable shafts mounted in bearings in pivoted and adjustable arms 13 and 14, respectively, on the main frame, and adjusting screws 15 and 16 serve to control the contact of said rollers through said arms and thus regulate the quantity of moisture carried forward by said rollers. The lower screw 16 is carried by a support 17 rigid with the top of the bearing for shaft 30, while screw 15 is carried by arm 14. Roll 8 is relatively larger than roll 9 and is held in working relation therewith by gravity, the primary support for roll 8 being by arms 18 fixed to and projecting forwardly and downwardly from table 4 and the secondary support being by adjustable slides 19 having channels 20 in which the ends of the roller shaft 21 of roll 9 have rotatable and sliding engagement.

The paper strip 2 is comparatively narrow, depending on the size of thread wanted, the width being, say three sixteenths of an inch, more or less. Consequently, said strip is easily broken especially when damp

or wet. But with the tensioning and dampening mechanism described the strip is stretched and carried forward to the spindle rapidly and without break, notwithstanding 5 the variable pulls and twisting strains imposed upon the strip. The friction or tension member *w* is of comparatively light weight, usually weighing less than a pound and in actual size about an inch across, and 10 say, two and a half inches long, and its main function is to steady the feed of the strip from roll *R* and prevent slack. Said member *w* has guide pins 22 in its bottom engaged in holes in the platform 4 and can be 15 bodily removed by hand to introduce the strip beneath.

Each paper roll *R* consists simply of a paper strip of narrow width wound about itself with accuracy, so that the rolls are as 20 narrow as the width of the strip itself and its actual diameter before unwinding is approximately twenty inches. The post or standard *f* which carries the roll serves as a guard on one side to keep the paper from 25 collapsing or working off on that side, while a blade 23 is fixed on the spool of said roll to confine the paper roll on the other side. The work of removing and replacing the rolls *R* is facilitated by providing a standard or support *f* with a stud shaft located 30 above the tensioning and dampening mechanism, and the feed of the paper strip is also in plain view from the roll to said mechanism. It will be seen in Fig. 2 that there is 35 a similar roll equipment for each of the several spindles *S*, five sets of tensioning and dampening rolls being shown in this instance and which represents one subdivision, say of ten, in the same machine, and each 40 and all the working units in a given section have corresponding paper rolls *R* and supporting means therefor.

The spindles of the tension rolls 8 being 45 engaged in open slots in the slide of bearing 19, the said roll has a free up and down play therein to obtain a uniform and sustained travel or supply of the strip to the spinning spindle with a minimum power. Heretofore, in this type of machine the practice 50 has been to provide a constantly sustained feed of the strip by a set of positively-acting feed rolls rotating at a fixed speed, thereby producing a continuous feed of a given length of paper in a given time regardless of the speed of the spindles or other parts. It follows that there was a tendency 55 to either overfeed or underfeed the paper and there was no harmonious co-operation between the parts. Hence, there was 60 also constant tendency to wavering in the supply of the strip and frequent breakage and imperfect spinning results. These troubles are very serious and materially diminish the amount of work done and necessitate much expensive supervision, but in the 65

present invention these troubles are mainly eliminated as the strip is drawn and fed and sensitively controlled in its entire travel from the roll *R* to the spindle *S*, and there is comparatively little of the former irregularity and breakage in the strips. It will also be noticed that by the present construction the feeding and travel of each strip is individually controlled from its roll 70 through to the spinning spindles and it 75 works out that each individual spindle practically controls the supply of paper thereto and the paper will not travel faster than it is taken care of by the spindle. Uniform dampening of the paper strip while under 80 motion is also essential to successful continuous operation of the machine, and to that end, the paper strip 2 is shifted longitudinally of the rolls by a reciprocable movement of shaft 6 during feeding operation of the strip. The contacting area of roll 8 is thereby not confined to a single narrow circumferential face; the width of said strip and the dampening area of roll 9 are 85 also not limited to the same narrow circumferential path, but on the contrary, new and changing contact surfaces are under action to maintain the proper feed and especially 90 the proper distribution of water to the strip.

The means for imparting reciprocable 95 movements to shaft 6 comprise a crank or eccentric 24 having a link connection 25 with shaft 6, said crank or eccentric being mounted on a short vertical shaft 26 mounted on suitable brackets 27 affixed to 100 one end of frame *F*. Rotation of shaft 26 is effected by a pinion 28 at its lower end and by a worm gear 29 on the shaft 30 of roller 11. Shaft 30 is driven by any suitable power connection, a gear 31 being 105 shown in this instance as a means to that end, see Fig. 2. Rolls 9 and 12 are driven by a train of gears 32, 33 and 34, respectively, located at the right of the machine, see Figs. 2, and 4, gear 32 being affixed 110 to shaft 30 of roll 11.

The platform 4 is supported by rack bars 35 and carries the arms 18 in which the rolls 8 are loosely and removably mounted, as hereinbefore described. Said rack bars 115 are slidably mounted on the main frame and the gear teeth 36 on said bars are engaged by toothed segments 37 fixed on an oscillatory shaft 38, whereby the platform 4 and parts carried thereby are adapted to 120 be moved forward or back relatively to the dampening roll 9 and the paper roll *R*. The shaft 38 is actuated by hand lever 38' or equivalent means.

As shown in Fig. 3 the parts are adjusted 125 to approximately but not quite the maximum rearward position and as shown the roll 8 rests upon the roller 9 in vertical axial alignment therewith and the roll 8 is free to move forward and upward under any 130

lifting strain imposed by the paper strip 2. A fifty spindle machine of five sections each requires the service of one or two attendants, and the removal of the spools on 5 the spinning spindles and the replacement of a new roll R and a strip 2 for renewed spinning operations are very quickly accomplished. The roll 8 may be set in an advanced position or forwardly of the roller 10 9 and it will drop down and still contact with the paper strip and roller 9 and still work as well as farther back but the time of exposure of the strip to the moisture on roller 9 will be correspondingly reduced. 15 This supplements the adjustments by the screws 15 and 16 to regulate the amount of moisture to be applied to the paper strip.

What we claim is:

1. A machine for spinning paper strips 20 having a main frame and a platform slidably mounted on the main frame, and slack take-up means for the strip mounted thereon comprising a loose weight to bear on the strip and an idler over which the 25 strip is adapted to pass from said weight, in combination with a dampening roller and a roll loosely supported in gravity-seating relations therewith for tensioning and dampening the paper strip carried forward 30 from said idler.

2. A machine for spinning paper strips

having a dampening roller, in combination with a slidable frame on the top and front of the machine having forwardly projecting arms and a tensioning roll thereon in gravity seating relations with the said dampening roller and an idler removably supported on said arms at different elevations, a friction device to tension the strip rearwardly of said idler, and an axial support for a 35 roll of paper located on a relatively higher plane than said friction device.

3. A machine to spin paper strips comprising spinning mechanism and dampening rolls in advance thereof, in combination 40 with a table and rack mechanism therewith adapted to slide the table, inclined arms fixed on said table, feed rolls slidably mounted on said arms and adapted to contact with said dampening rolls, idlers 45 mounted on the base of said arms and weights on said table in advance of said idlers and adapted to tension the paper strip.

In testimony whereof we affix our signatures in presence of two witnesses.

EDWARD SCHMIDT.
